UNITED STATES PATENT OFFICE.

HUBERT C. HART, OF UNIONVILLE, CONNECTICUT.

DESIGN FOR A FORK.

SPECIFICATION forming part of Design No. 14,947, dated April 8, 1884.

Application filed February 7, 1884. Term of patent 7 years.

To all whom it may concern:

Be it known that I, HUBERT C. HART, of Unionville, in the county of Hartford and State of Connecticut, have invented and produced 5 a new and original Design for Forks; and I do hereby declare that the following is a full, clear, and exact description of the invention, which will enable others skilled in the art to which it appertains to make and use the same, reference being had to the accompanying drawings, which form a part of this specification, and in which—

Figure 1 is a view of my newly-designed fork. Fig. 2 is an edge view of the same, and 15 Figs. 3, 4, 5, and 6 are cross-sections on the dotted lines in Fig. 1.

Similar letters of reference indicate corresponding parts in all the figures.

My design relates to forks for table use, and 20 the handle A tapers upward in width and downward in thickness, and the upper end of the handle, at the point where the shank B of the prongs C passes over into the handle, forms a shoulder, produced by a groove, D, above

which is an enlargement, E, of the shape of a 25 truncated cone, slightly flattened, and the flattened sides of the enlargement are depressed at their upper ends at F, being continued in the flat sides of the shank.

Having thus described my design, I claim 30 and desire to secure by Letters Patent of the United States—

The design for a fork, consisting of a handle tapering upward in width and downward in thickness, a groove around the upper end of 35 the handle, an enlargement above the said groove of a truncated conical shape, slightly flattened, and a flat shank having its flat sides forming depressed continuations of the flat sides of the enlargement, as shown and set 40 forth.

In testimony that I claim the foregoing as my own I have hereunto affixed my signature in presence of two witnesses.

HUBERT C. HART.

Witnesses:

CARLOS L. MASON,
WABIE SMITH.
